TOY BUILDING BLOCK

Robert Daenen, Erembodegem, Belgium, assignor to Dart Industries Inc., Los Angeles, Calif.

Filed June 5, 1972, Ser. No. 259,417

Term of patent 14 years

Int. Cl. D21—01

U.S. Cl. D34—15 FF

FIG.—1

FIG.—6

FIG.—4

FIG.—2

FIG.—3

FIG.—5

FIG.—7

FIG.—8

FIG. 1 is a perspective view of a toy building block component showing my new design;

FIG. 2 is a front elevational view;

FIG. 3 is a right side elevational view;

FIG. 4 is a left side elevational view;

FIG. 5 is a rear elevational view;

FIG. 6 is a top plan view;

FIG. 7 is a bottom plan view; and

FIG. 8 is a perspective view of a toy building block showing a modified form of my new design, wherein the contrast between the surface textures is omitted.

I claim:

The ornamental design for a toy building block, substantially as shown and described.
